Primary Examiner — Leanne Was-Englehart

Assistant Examiner — Devin Kelly

(57) **CLAIM**

The ornamental design for a charger, as shown and described.

DESCRIPTION

FIG. 1 is a front, top and right-side perspective view of the charger showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof;

FIG. 9 is a front perspective view thereof, shown in an alternate state; and,

FIG. 10 is a perspective view of the charger shown in a position of use with environmental subject matter.

The broken lines on FIG. 10 depicting environment form no part of the claimed design.

1 Claim, 10 Drawing Sheets
